US00D833382S

(12) **United States Design Patent** (10) **Patent No.:** **US D833,382 S**
(45) **Date of Patent:** **** Nov. 13, 2018**

(54) **PHOTOVOLTAIC ROOF TILE**

(71) Applicant: **SolarCity Corporation**, San Mateo, CA (US)

(72) Inventors: **Remy Labesque**, San Francisco, CA (US); **Daniel Flanigan**, San Francisco, CA (US); **Jack West**, San Francisco, CA (US); **Brian Atchley**, Petaluma, CA (US); **Brian West**, San Francisco, CA (US); **Charles Almy**, San Francisco, CA (US)

(73) Assignee: **SolarCity Corporation**, San Mateo, CA (US)

(**) Term: **15 Years**

(21) Appl. No.: **29/582,645**

(22) Filed: **Oct. 28, 2016**

(51) LOC (11) Cl. **13-02**

(52) U.S. Cl.

USPC **D13/102**

(57) **CLAIM**

The ornamental design for a photovoltaic roof tile, as shown and described.

DESCRIPTION

FIG. 1 is a bottom front perspective view of a photovoltaic roof tile showing the claimed design;

FIG. 2 is a top front perspective view thereof;

FIG. 3 is a bottom rear perspective view thereof;

FIG. 4 is a front view thereof;

FIG. 5 is a rear view thereof;

FIG. 6 is a left side view thereof;

FIG. 7 is a right side view thereof;

FIG. 8 is a bottom view thereof; and

FIG. 9 is a top view thereof.

FIG. 10 corresponds with the enlarged fragment view labeled FIG. 10 on FIG. 1; and,

(Continued)

FIG. 11 corresponds with the enlarged fragment view labeled FIG. 11 on FIG. 3.
